PROPRIETOR

George Walter

BY

J. T. Dowling ATTORNEY.

UNITED STATES PATENT OFFICE.

GEORGE WALTER, OF BALTIMORE, MARYLAND.

DESIGN FOR A BADGE, BUTTON, OR PIN.

58,649.

Specification for Design.

Patented Aug. 2, 1921.

Application filed October 11, 1920. Serial No. 416,327. Term of patent 3½ years.

To all whom it may concern:

Be it known that I, GEORGE WALTER, a citizen of the United States of America, residing at Baltimore, State of Maryland, have invented a new, original, and ornamental Design for Badges, Buttons, or Pins, of which the following is a specification, reference being had to the accompanying drawing, forming part thereof.

The figure is a plan view of the badge, button, or pin, showing my new design.

I claim:

The ornamental design for a badge, button, or pin, as shown.

GEORGE WALTER.
